CHARLES LEA, OF BOSTON, MASSACHUSETTS, ASSIGNOR TO AMERICAN WARP DRAWING MACHINE COMPANY, OF BOSTON, MASSACHUSETTS, A CORPORATION OF MAINE.

SPACING-CLAMP FOR WARP-THREADS AND OTHER PURPOSES.

1,346,498.

Specification of Letters Patent.

Patented July 13, 1920.

Application filed August 31, 1915, Serial No. 48,221. Renewed October 11, 1919. Serial No. 330,140.

To all whom it may concern:

Be it known that I, CHARLES LEA, citizen of the United States, and resident of Boston, Massachusetts, have invented certain new and useful Improvements in Spacing-Clamps for Warp-Threads and other Purposes, of which the following is a specification.

This invention relates to spacing clamps and is more particularly intended for use in the holding and spacing of warp threads preparatory to or during the weaving operation, although said clamps may be used in other relations also.

The clamps commonly used for this purpose consisted of a comb-like member combined with a trough-like cover adapted to be slipped over the ends of the comb teeth after the warp or other threads have been laid between the teeth. Obviously, such thin metal cover when dented or bent, which easily happens, cannot readily be applied to the comb or spacing member.

It is the object of the present invention to improve and simplify the construction of these devices by providing a spacing clamp whose efficiency is not likely to be impaired by careless handling and which is positively locked together in operative position, while at the same time cheapening and simplifying the construction, and also rendering it capable of use on a warp beam or spool that is of shorter length than the clamp itself.

In the accompanying drawings I have illustrated the preferred form embodying the principles of the present invention, in which—

Figure 1 is a side elevation of the clamp closed for use and containing the warp threads.

Fig. 2 is a detail view in side elevation of a portion of the spacing member or comb.

Fig. 3 is an end elevation of the clamp showing the locking member inserted in the retaining eyes of the clamp.

Fig. 4 is a view of a modified form of retaining member.

In the practice of this invention, the comb member may be most conveniently and cheaply formed of spring metal whose teeth have a slight degree of resilience. When made of such material it embraces the back or solid portion *a* and the properly spaced

teeth *a'* between which the warp threads are placed, the teeth being pointed preferably to facilitate insertion of the warp threads. The 55 teeth *a'*, or a portion of them at least, are formed with off-sets *a''*, thus producing a series of open loops or eyes, some of which face to one side of the comb and others of which face to the opposite side in the particular form shown for the purpose of receiving a suitable retaining member which closes the spaces between the teeth to prevent the warp threads from falling out.

This retaining member *b* may consist simply of a wire rod which is preferably of a diameter to fit tightly into the retaining eyes formed in the comb teeth. When the comb teeth are made of resilient material, such as thin steel or the like, they will be slightly 70 spread apart by the inserted rod and by pinching the rod frictionally tend to prevent any accidental endwise displacement of the retaining member.

As shown in Fig. 4, the retaining member 75 may consist simply of a cord *b'* secured to a threading needle *b''*, which facilitates drawing the thread through the eyes of the teeth.

It will be observed that the locking member, whether consisting of a cord or a rod, 80 is positively held against outward movement under the tension or weight of the warp threads and yet is very easily removed by withdrawal endwise. To facilitate the insertion of the retaining member, it may be 85 tapered at one end, as shown in the drawings, which makes it easier to slightly spread apart or open the retaining loops or eyes of the comb teeth.

One very important characteristic of the 90 clamp having this construction is that it is sufficiently flexible to allow it to be curled or bent diagonally around the warp spool between the spool heads, even when the clamp is of greater length than the direct 95 measurement between the two heads of the warp spool. This is a feature of practical importance, since the same clamp can be used on spools carrying a different number of warp threads to the inch, since the extra 100 length of the comb or clamp can be disposed of by bending it around the warp beam in a diagonal or spiral direction as the warp threads can be just as readily wound over

this flexible clamp in a spiral position as when it is arranged parallel to the axis of the beam.

What I claim is:

- 5 1. A spacing clamp for warp threads or the like embracing a spacing member formed with a series of properly spaced teeth having off-set portions arranged in axial alinement to form a series of retaining eyes or loops adapted to receive a retaining member, and a retaining member adapted to be inserted between the off-set portions of said teeth by which it is removably locked in operative position to prevent the threads from falling out of place, substantially as described.
- 10 2. A spacing clamp for warp threads or the like consisting of a comb-like member whose teeth are formed with off-set open recesses or loops, some of which face toward one side and others toward the opposite side, and arranged at the same level longitudinally of the comb, and a retaining member adapted to be inserted endwise through the off-set loops so as to be positively held against outward displacement, substantially as described.
- 15 3. A spacing clamp embracing in its construction a comb having resilient teeth formed with open off-set portions, some facing to one side and others to the other side to form retaining eyes, a longitudinal retaining member capable of being passed through said eyes longitudinally to close the open ends of the space between the teeth, said retaining member being of a diameter to be pinched by the resilient teeth to hold it frictionally against longitudinal slipping, substantially as described.
- 20 4. A spacing clamp embracing in its con-

struction a comb-like member having teeth formed to interlockingly embrace a retaining rod, and a retaining rod insertible endwise through the teeth and positively held thereby against outward displacement, substantially as described.

5. The combination of a comb having spring teeth, corresponding portions of the different teeth being off-set in opposite directions, a retaining rod formed to be inserted between said off-set portions, said retaining rod having one end tapered, substantially as described.

6. The combination of a flexible comb having a series of flexible spacing teeth, and a flexible retaining member adapted to form a detachable engagement with said teeth to hold the interposed threads in position, the comb and the retaining member when assembled for use being sufficiently flexible to be wrapped diagonally around the warp spool, substantially as described.

7. A spacing clamp for warp threads or the like, embracing in its construction a comb-like structure having a flexible back or base, and a series of laterally projecting parallel teeth spaced apart to receive warp threads between them, said teeth being formed to interlockingly engage a longitudinal warp-retaining member, intermediate of their ends, and a flexible warp-retaining member adapted to be removably held in warp-retaining engagement with said teeth intermediate of their ends, whereby the entire clamp may be readily bent around the warp spool in a helical or spiral direction, substantially as described.

In witness whereof, I have subscribed the above specification.

CHARLES LEA.
